UNITED STATES PATENT OFFICE.

FRED C. HOWE, OF NEW HAVEN, CONNECTICUT.

ADJUSTABLE LAMP.

1,124,903.

Specification of Letters Patent. Patented Jan. 12, 1915.

Application filed March 26, 1914. Serial No. 827,440.

To all whom it may concern:

Be it known that I, FRED C. HOWE, a citizen of the United States, residing at New Haven, in the county of New Haven and State of Connecticut, have invented certain new and useful Improvements in Adjustable Lamps, of which the following is a specification, reference being had therein to the accompanying drawings.

10 My invention relates to a new and improved adjustable lamp, having for its object, among other things, to provide means for moving the lamp into any desired position, within a limited range, about a common center, and independently into a single predetermined position about the same center quickly and easily.

With these, and other objects in view, my invention consists in the adjustable lamp, having certain details of construction, and combinations of parts, as will be herein-after described and more particularly pointed out in the claims.

Referring to the drawings, in which like numerals of reference designate like parts in the several figures; Figure 1 is a fragmentary side elevation of my improved lamp; Fig. 2 is an end view of the parts shown in Fig. 3; Fig. 3 is a side elevation 30 of the cup and guide ball with that portion of the lamp body adjacent thereto; Fig. 4 is a side elevation of my improved lamp, illustrating particularly the mechanism for shifting the lamp body and guide ball as 35 a unit to a predetermined position upon one side of the center of the operating shaft; Fig. 5 is a similar view with the lamp body and the adjacent parts in said predetermined position; Fig. 6 is a detail view of a portion 40 of the two-part shaft; and Fig. 7 is a perspective view of the journal socket.

The invention is illustrated in the drawings as applied to an electric lamp, but it may be used equally as well for any type 45 of mechanism, wherein it is designed that one of the members thereof should be moved about a common center. I do not, therefore, desire to be limited in the use of this device to a lamp, its particular application thereto 50 in this case being merely for the purpose of showing one form or method of the embodiment thereof.

In the drawings the lamp body is designated by the numeral 1, within which is an 55 incandescent lamp 2 of the ordinary type, current being conducted thereto through a wire 3.

Fixed within the rear end of the body member 1 is the cup member 4, within which is the curved slot 5, having teeth 6 in one edge thereof.

The numeral 7 designates a fixed member, within which is a journal 8 that forms a bearing for the shaft 9 that is rotatably mounted therein. This shaft is also journaled in a bracket 10, having a thumb screw 11 threaded therethrough, the inner end of which bears against said shaft. One end of this shaft projects through a guide ball 12 secured thereon, and has a pinion 13 thereon that projects into the slot 5 with the teeth thereon meshing into the teeth 6 in one side of the slot. The center of this guide ball 12 is coincident with the center of the cup 4, and is held in engagement therewith by the rear end of the body member 14, being turned inwardly, as shown particularly in Figs. 1 and 3, over the rear portion of the ball, so as to insure an inseparable engagement of the cup with the body member attached thereto, and said ball. The body member is additionally supported by the bracket 15 connected with said body member and the interposed spring 16.

In Figs. 1 and 3 the lamp body is illustrated with its axis coincident with that of the shaft 9, and is held in such position by the contact of the screw 11 with said shaft. To vary the position of the lamp body about the center of the ball 12, the shaft 9 is rotated through the thumb nut 17, and the toothed engagement of the pinion 13 with the toothed side of the slot 5 positively moves the said lamp body about the center of said ball, the spring 16 yielding sufficiently to permit this movement. The parts are locked in their several adjusted positions by the screw 11, and returned to their initial positions by unloosening this same screw, at which time the spring 16 will contract and draw the lamp body back to the position shown in Fig. 1, a manual rotation of the shaft 9 facilitating this action if necessary.

There are unlimited uses to which this lamp, as herein described, may be put, but if applied particularly to automobiles there is one position more than any other into which the lamp may be conveniently placed for utility, and that is, to throw its rays of light downwardly. Its use in this position is more common than in any other, and to provide for this movement, as well as for the universal movement above described, I

split the shaft 9 in two parts, the forward part being a stub shaft and designated by the numeral 18, having a wing 19 thereon, which is movable within a slot 20 in the shaft 9 and pivotally connected therewith by the pintle 21.

To one side of the fixed member 7 I secure a journal socket 22, upon one side of which is an outwardly flaring throat portion 23, 10 When the parts are in the position shown in Fig. 4, the adjustment of the position of the body member 1 about the center of the guide ball 12 is accomplished in the manner heretofore described, the inner end of the stub 18 shaft 18 rotating within the socket journal 22.

To quickly and easily throw the lamp body and guide ball downwardly, the shaft 9 is moved longitudinally instead of being rotated, at which time the stub shaft 18 is rocked upon its pivot mounting and is drawn downwardly by gravity, the spring 16 not being strong enough to resist the combined weight of the lamp body, the ball 12 and the stub shaft 18 when thrown directly upon it, the then position of the lamp body, ball and spring being shown in Fig. 5. It can be locked in this position by the thumb screw 11, as will be readily understood.

To return the parts to their initial position the shaft 9 is again moved longitudinally, but in the opposite direction, and the wing 19 upon the stub shaft 18 engages the open throat of the journal socket 23 and lifts the body member and the parts immediately connected therewith until the axis of the stub shaft 18 and the shaft 9 are coincident, its then position being the same as that shown in Fig. 4.

There are minor changes and alterations that can be made within my invention, and I would therefore have it understood that I do not limit myself to the exact construction herein shown and described, but claim all 15 that falls fairly within the spirit and scope of my invention, as set forth in the appended claims.

Having described my invention, what I claim as new and desire to secure by Letters 50 Patent, is,—

1. The combination with a body member, having a cup member therein with an irregular shaped slot; of a globular member within said cup member; and means connected with said globular member and engaging the slot in said cup member, whereby movement of said globular member about a fixed axis is transmitted into a movement by said body member about the center 65 of said globular member.

2. The combination with a cup member, having a slot therein with one toothed edge;

of a globular member within said cup member; a shaft connected with said globular member and rotating about a fixed axis; a 65 member connected with said globular member, projecting into the said slot in said cup member and meshing with said toothed edge; and means for securing said shaft against rotation in any of its adjusted positions.

3. The combination with a cup member, having a slot therein with one toothed edge; of a globular member within said cup member; a shaft connected with said globular member and rotating about a fixed axis; a 75 pinion connected with said globular member, projecting into said slot in said cup member and meshing with said toothed edge; and spring means for returning said cup member to a predetermined position.

4. The combination with a two-part shaft; of a hinged connection between said parts; a globular member connected with one of said parts; a cup member in part surrounding said globular member, and having an irregularly shaped slot therein; an element connected with said globular member and projecting into said slot, whereby movement of said globular member is transmitted to said cup member.

5. The combination with a two-part shaft; of a globular member connected with one of said parts; a pinion connected with said globular member; a cup member in part 95 surrounding said globular member and having a slot therein, one edge of which is provided with teeth which are engaged by the teeth in said pinion; and means for mounting said shaft so that it may be rotated and 100 moved parallel with its axis.

6. The combination with a two-part shaft; of a globular member connected with one of said parts; a pinion connected with said globular member; a cup member in part 105 surrounding said globular member and having a slot therein, one edge of which is provided with teeth which are engaged by the teeth in said pinion; means for mounting said shaft so that it may be rotated and 110 moved parallel with its axis; and a journal socket surrounding said shaft and so arranged that in one position of said shaft parts, said socket will hold them with their axes coincident, but in another position will 115 allow them to relatively shift so that their axes are at an angle to each other.

In testimony whereof I affix my signature in presence of two witnesses.

FRED C. HOWE.
